FIG. 1

FIG. 3

FIG. 2

FIG. 4

FIG. 5

FIG. 6

FIG. 7

FIG. 8

FIG. 9

FIG. 10

FIG. 1 is a perspective view of a combination headset and radio receiver showing my new design;

FIG. 2 is a front elevation thereof;

FIG. 3 is a rear elevation thereof;

FIG. 4 is a top plan view thereof;

FIG. 5 is a partial side elevation thereof, the opposite side being a mirror image of the side shown;

FIG. 6 is a front elevation of a modified embodiment of the combination headset and radio receiver illustrated in FIG. 1;

FIG. 7 is a rear elevation thereof;

FIG. 8 is a top plan view thereof;

FIG. 9 is a left side elevation thereof, the right side being a mirror image; and

FIG. 10 is a bottom plan view thereof.

In the two embodiments of the invention, an outer portion of each headphone is shaped to represent a football helmet.

This is a continuation-in-part of design application Ser. No. 329,016, filed Feb. 2, 1973 and now abandoned.

I claim:

The ornamental design for a combination headset and radio receiver, as shown and described.
